FIG. 5.

FIG. 6.

Geo. H. Kimmel. ATTORNEY.

UNITED STATES PATENT OFFICE.

JAMES S. PATTERSON, OF ABILENE, TEXAS, ASSIGNOR OF ONE-FOURTH TO WILLIAM E. PATTERSON AND ONE-FOURTH TO J. S. PATTERSON, JR., BOTH OF ABILENE, TEXAS.

FAN MOTOR.

Application filed October 6, 1923. Serial No. 666,950.

To all whom it may concern:

Be it known that I, JAMES S. PATTERSON, a citizen of the United States, residing at Abilene, in the county of Taylor and State of Texas, have invented certain new and useful Improvements in Fan Motors, of which the following is a specification.

This invention relates to weight operated fan motors, and has for one of its objects 10 to improve the construction and increase the efficiency and utility of devices of this character.

With this and other objects in view the invention consists in certain novel features 15 of construction as hereinafter shown and described and then specifically pointed out in the claims, and in the drawings illustrative of the preferred embodiment of the invention—

20 Figure 1 is a side elevation of the improved device.

Figure 2 is a transverse section enlarged on the line 2—2 of Figure 1 looking in the direction of the arrow.

25 Fig. 3 is a longitudinal sectional elevation.

Fig. 4 is a plan view with the upper portion of the enclosing casing removed.

Figure 5 is a sectional detail of the winding drum and the drive pinion thereon, illustrating the winding mechanism.

30 Fig. 6 is a transverse section on the line 6—6 of Fig. 5.

The improved fan operative mechanism is enclosed in a divided casing formed of a 35 lower or base portion 10 and upper or cover portion 11 preferably united by flanges as shown at 12.

Formed in the opposite sides of the base portion of the casing are a plurality of half 40 bearings 13 in each pair of which shafts are supported either stationary or rotative as

may be preferred. One of the shafts 14 is the main drive shaft while the remaining shafts 15, 16 and 17, are arranged to support

45 the transmission gearing. The cover portion 11 is formed with opposing half bearings, represented at 19, to bear over the terminals of all the shafts. Mounted to rotate with the drive shaft 14 is a winding drum

50 20, on which a relatively long cable 21 is wound and with a relatively heavy weight 22, at the free end of the cable below the casing 10—11.

Mounted loosely on the drive shaft 14 is a

gear pinion 23, and mounted loosely on the 55 shaft 15 is a larger gear 24, in constant engagement with the pinion 23. Mounted loosely on the shaft 16 is a pinion 25 in constant engagement with the larger gear 24. Mounted loosely upon the shaft 16 and attached to or formed integral with the pinion 25 is a gear 26.

Mounted loosely on the shaft 17 is a pinion 27 in constant engagement with the 60 gear 26. 65

Mounted loosely on the shaft 18 and attached to or integral with the pinion 27 is a relatively large gear 28.

Mounted loosely on the shaft 16 is a pinion 29 constantly engaged by the larger gear 70 28.

Mounted loosely on the shaft 16 and attached to or integral with the pinion 29, is a relatively large gear 30.

Mounted loosely upon the shaft 15 is a 75 pinion 31 in constant engagement with the gear 30.

Mounted loosely on the shaft 15 and attached to or integral with the pinion 31 is a relatively large gear 32. 80

Mounted for rotation in one of the bearings of the drive shaft 14 is the hub or sleeve portion 33 of a fan 34, the hub having a socket to receive and support one end of the shaft 14. Mounted upon or attached to the hub 33 of the fan, is a pinion 35, constantly engaged by the gear 32. 85

Each of the shafts is shown provided with suitable stop collars to retain the shafts in 90 position in the casing.

For the purpose of illustration four of the transmission shafts are shown, but a greater or lesser number may be employed if required.

By this arrangement, the force of the 95 weight is utilized to transmit motion to the fan at high speed from relatively slow motion of the drum shaft.

Formed upon or attached to the drum 20 is a ratchet 36 and extending from the hub 100 of the pinion 23 is an arm 37 carrying a pawl 38 to engage the teeth of the ratchet. The shaft 14 is extended at one end and formed square as at 39 to receive a winding key, not shown. By this arrangement the cable may be wound upon the drum when necessary. 105

The improved device is simple in con-

struction and may be of any required size or capacity.

Having thus described the invention, what is claimed as new is:—

- 5 1. A device of the class described, comprising a support having transversely aligned bearings, a shaft journalled at one end in one of said bearings, a hub element bearing a gear pinion and journalled in the other of said bearings, said hub element formed with a seat to receive the other end of said shaft, a winding drum mounted to rotate with said shaft and carrying a ratchet wheel, a gear pinion rotative upon said shaft and carrying a pawl engaged by said ratchet, a cable having a weight attached thereto at one end and attached at the other end to said drum and adapted to be wound thereon, and a train of gears carried respectively by the remaining aligned shafts and operating between the pinion of said shaft and the pinion of said hub element, whereby said drum is rotative under the influence of said weight and the motion of the drum communicated to the hub.

- 25 2. A device of the class described, com-

prising a support having a plurality of transversely aligned pairs of bearings, a shaft journalled at one end in one of said aligned bearings, a hub element bearing a gear pinion and journalled in the other of said aligned bearings, said hub element formed with a seat to receive the other end of said shaft, a winding drum mounted to rotate with said shaft and carrying a ratchet wheel, a gear pinion rotative upon said shaft and carrying a pawl engaged by said ratchet, a cable having a weight attached thereto at one end and attached at the other end to said drum and adapted to be wound thereon, and a train of gears carried respectively by the remaining aligned shafts and operating between the pinion of said shaft and the pinion of said hub element, whereby said drum is rotative under the influence of said weight and the motion of the drum communicated to the hub.

In testimony whereof, I affix my signature hereto.

JAMES S. PATTERSON.
